UNITED STATES PATENT OFFICE

142,916

DESIGN FOR A MEAT TENDERIZING MACHINE

Joseph P. Spang, Milton, Mass.

Application February 24, 1945, Serial No. 118,115

Term of patent 14 years

(Cl. D55—1)

To all whom it may concern:

Be it known that I, Joseph P. Spang, a citizen of the United States, residing at Milton, in the county of Norfolk and Commonwealth of Massachusetts, have invented a new, original, and ornamental Design for Meat Tenderizing Machine, of which the following is a specification, reference being had to the accompanying drawing forming a part thereof, in which the figure is a view in perspective of a meat tenderizing machine, showing my new design.

The back is substantially plain except for the continuation of the horizontal rib illustrated at the front in the drawing and which rib passes entirely around the machine.

I claim:

The ornamental design for a meat tenderizing machine, substantially as shown and described.

JOSEPH P. SPANG.
